MANUFACTURE OF A WALL

Roscoe Dorsett, 551 Westwood Ave., Dayton, Ohio

Filed Aug. 24, 1955, Ser. No. 530,285

1 Claim. (Cl. 18—60)

Buildings with concrete or masonry walls have been constructed in the past, having cellular walls with an air space between the inner and outer portions of the walls. However, these walls have been so constructed that they did not provide a complete moisture barrier between the inner and outer portions of the wall. Also these walls have not provided an excellent resistance to the passage of heat from one portion of the wall to the other portion of the wall.

Those who are acquainted with chemicals and metals know that most metals are subject to chemical and electrolytic attack. Aluminum foil used in the construction of masonry and concrete buildings is subjected to attack by the elements of concrete and masonry materials.

All who have knowledge in the art of building know that it is desirable to provide an air space in the wall members. They also know that because of the porosity of concrete it is desired that a moisture barrier be provided to prevent moisture passing through the wall. They are aware of the need of a wall that resists the passing of heat. They know the value of providing a design that will improve the appearance of the wall. Heretofore walls have not incorporated these functions.

An object of this invention is to provide an improved method for constructing concrete walls in which one or more continuous air spaces exist, the air space being lined with a thin sheet or foil of metal.

Another object of this invention is to provide a means of constructing concrete walls having an inner and an outer member, the outer member being either plain, or having an imprinted design, and there being a single or plurality of walls of concrete or other material spaced between the inner and outer members.

Another object of this invention is to provide a thin metal sheet or foil moisture barrier and heat reflector, having one side coated with asphaltum or other suitable material not subject to chemical attack by elements of concrete upon which a layer of sand or other material to which mortar or concrete will adhere has been applied.

Another object of this invention is to provide a means of lining cellular wall air spaces with metal foil moisture barrier and heat reflector.

Other advantages and objects inhere in the construction of parts and mode of operation. From the following description the objects and advantages shall become more apparent.

In the drawings:

Figure 1 is a fragmentary side elevational view of a section of wall made according to this invention.

Figure 2 is a horizontal cross-section of Figure 1.

Figure 3 is a curvilinear view of a sheet of metal foil prepared according to this invention with a coating of asphaltum and a layer of sand adhering to the asphaltum.

Figure 4 is an isometric perspective view of a section of matrix made according to this invention.

Referring to the drawings in detail:

In the construction of poured concrete wall members, form members 5 and 6 of any suitable construction

2

may be used. Form members 1 and 7 of any suitable construction may also be used. Such mold construction may be of any character to permit the metal foil 4 to be maintained in flat condition against the mold or plywood 5 and to permit unset concrete to be placed and be maintained in flat form against a layer of relatively small particles adherent to both the concrete and the asphaltum on said foil 4 until the concrete sets to provide a concrete wall member or panel 3 with a metal foil face 4, 10 which may be produced in any manner for a building.

The wall member 3 may be erected as a wall for a building under any conditions and in any manner desired.

As one example, the form members 1, 5, 6 and 7 may be of any usual construction which holds the form members 15 1, 5, 6 and 7 in selected and spaced position. The frame members 1 and 6 of the form members may support any smooth surface opposite layers of material, such as plywood 5 and 7 to permit the concrete 3 to be made as a flat member for a building. If desired, the plywood surface 7 may be used in bare condition or it may be covered by a rubber matrix 2 which may be held along the inner face of the plywood 7.

The matrix 2 may be made of any suitable material such as rubber and is placed in position against and secured to the inside surface of the plywood 7 in a manner that will permit the removal of the form from the concrete wall member without removing the matrix. This can be accomplished by any one of a number of ways. A simple way of installing the matrix is to install metal 25 eyelets near the top edge of the matrix through which pins may be driven into the form. The matrix may be suspended in its proper position for any required distance.

The moisture barrier and heat reflector 4 is placed in 35 contact with the plywood 5.

The sheet of metal foil 4 in Figure 3 has been prepared according to this invention. The reflective side is indicated by the number 11. The number 10 indicates the 40 opposite side of the sheet of metal foil which has been prepared in a manner that facilitates its adherence to wet concrete or other similar wet materials, such as, for example, gypsum and plaster.

The moisture barrier and heat reflector can be made by any one of several methods. A simple method is to 45 spread the sheet of metal on a flat surface and apply by brush, spraying, pouring, or other means of application, a coating of asphaltum or other suitable material in liquid state. A layer of sand or other material to which concrete will adhere is now spread over the layer of asphaltum. The sand becomes imbedded in the asphaltum and is bound thereby to the metal sheet. The sand coming in 50 contact with the wet concrete becomes an element of the concrete through the action of the cement in the concrete. The coating of asphaltum also prevents the metal coming in contact with the concrete, thereby protecting the metal from chemical and/or electrolytic attack by the elements of the concrete. The asphaltum backing may be strengthened by the admixture of mineral 55 and/or other fibrous material.

Having assembled the form members 1, 5, 6 and 7, having positioned the matrix 2 in place on plywood 7, and having placed the moisture barrier and heat reflector 10, 11 in place on plywood 5, the form or mold is ready for filling with concrete 3 or similar material.

60 The form members being assembled and arranged in their proper place, the concrete is then poured into the space provided by the forms. The wet concrete coming in contact with the sand or other material imbedded in the asphaltum backing on the moisture barrier and heat reflector becomes a part of the concrete.

65 After waiting for a period of time for the concrete to become sufficiently solidified, the forms are removed.

The removal of the forms having been completed, the matrix is next removed. The matrix having ridges, beads and configurations to mold or cast a likeness of stone or brick as shown in 14, Figure 4 on a backing of rubber or some suitable material, the surface, 13 in Figure 4, being smooth, or having indentations, beads or grooves may hold to the solidified concrete after the form members have been removed. However, a reasonable force applied in a manner to pull the matrix from the concrete will not affect the release, and the wall will retain the design, shape or imprint of the matrix.

The concrete wall member is now complete with moisture barrier and heat reflector having become an integral member.

While the specific method now preferred has been disclosed as required by statute, such method may be modified in any manner coming within the scope of the claimed method which follows.

Having thus described my invention, I claim:

The method of manufacture of a wall for a building comprising: coating a flexible metal foil with asphaltum; coating said asphaltum with a layer of relatively small solid particles adherent to both concrete and said asphaltum; maintaining said foil in flat condition against a wall mold for a building; introducing unset concrete in the form of a flat wall against said layer of relatively small solid particles; maintaining said concrete in

the form of a flat wall against said particles until said concrete sets; and removing said wall mold to provide a concrete wall with a metal foil face.
